UNITED STATES PATENT OFFICE.

ROSCOE WALTER THAYER, OF WILLOW CREEK, MONTANA.

PIPE-WRENCH.

1,150,078.

Specification of Letters Patent. Patented Aug. 17, 1915.

Application filed January 12, 1915. Serial No. 1,886.

To all whom it may concern:

Be it known that I, ROSCOE WALTER THAYER, a citizen of the United States, residing at Willow Creek, in the county of Gallatin, State of Montana, have invented certain new and useful Improvements in Pipe-Wrenches; and I do hereby declare the following to be a full, clear, and exact description of the invention, such as will enable others skilled in the art to which it appertains to make and use the same.

This invention relates to improvements in pipe wrenches.

An object of the invention resides in the provision of a simple, durable and inexpensive wrench of the above type, in which novel means are embodied whereby the jaws thereof may be conveniently adjusted with relation to each other to accommodate pipes of greater or less diameter.

With the above and other objects of similar nature in view, the invention consists in the construction, combination and arrangement of parts, set forth in and falling within the scope of the appended claim.

In the drawing:—Figure 1 is a front elevation of a wrench constructed in accordance with the invention. Fig. 2 is a side view thereof. Fig. 3 is a view similar to Fig. 1 with parts thereof broken away, and Fig. 4 is a similar view taken on the line 4—4 of Fig. 1.

Referring now more particularly to the drawing, the wrench comprises a handle 10 having formed at one end thereof a stationary jaw 11, the gripping surface of the latter being curved and serrated as at 12, as is usual in tools of this nature.

Arranged at opposite sides of the jaw 10 and pivoted as at 13 to swing longitudinally thereof, are a pair of elongated links 14, the free ends of which project beyond the gripping face 12 of the jaw and are rigidly connected together by means of a transverse pin 15.

Slidably mounted between the links 14 and adjustable with respect to the stationary jaw 11, is a movable jaw 16, the gripping face of which is likewise curved and serrated as at 17 to co-operate with the stationary jaw in engaging and clamping the object to be turned.

Formed transversely through the shank 18 of the movable jaw and adjustably receiving the pin 15 of the links 14 is a longitudinal slot 19, said slot being provided

in the side wall thereof adjacent the stationary jaw, with a plurality of downwardly inclined transverse notches 20, in which said pin is adapted to be interchangeably engaged whereby to secure the jaw in its various adjusted positions.

To prevent lateral displacement of the shank 18 with respect to the handle 10, there are secured to and extended similarly from opposite sides of the latter a pair of spaced keeper plates 21, which closely embrace the shank and have connecting their free ends a transverse pin 22, said pin being designed to engage the outer edge of the shank and limit movement thereof away from the handle.

Disposed in the handle 10 beneath each of these plates 21 and opening toward the shank 18 is a groove or pocket 23 in which is seated a helical spring 24, the outer ends of said springs engaging the adjacent edge of the shank to urge the same outwardly upon the pin 15 as a pivot, and yieldably retain the jaw 16 in gripping relation with the jaw 11.

It will be noted that the plates 21 are also provided with grooves or pockets 25, formed by pressing the metal outwardly as is readily apparent, these grooves registering with those in the handle 10 and coacting therewith to suitably house the springs 24. It will further be noted that the grooves 25 in the plates extend to a point beyond the adjacent edge of the shank 18 and thus serve to prevent lateral displacement of the springs when the jaw 16 is adjusted with respect to the jaw 11.

Having thus fully described the invention, to adjust the jaws 11 and 16 to accommodate pipes of different sizes, pressure is exerted upon the free end of the shank 18, and against the action of the springs 24, to disengage the pin 15 from the related notch 20. The jaw 16 is then moved as desired either toward or away from the jaw 11 with the shank 18 sliding freely between the springs 24 and pin 22, the pin 15 riding along the slot 19, and again engaging in one of the notches 20 when pressure upon the shank is removed.

What is claimed, is:

A pipe wrench comprising a handle, a jaw at one end of the handle, a second jaw adjustable toward and away from the first named jaw and provided with a shank having a longitudinal slot and notches formed

in one wall of the slot, links having their inner ends pivoted to opposite sides of the first named jaw and their outer ends loosely embracing said shank, a pin connecting the outer ends of said links and slidably positioned in the slot for interchangeable engagement in said notches, and means for yieldably holding said pin in engagement

with the notches to retain said second named jaw in adjusted position.

In testimony whereof, I affix my signature, in the presence of two witnesses.

ROSCOE WALTER THAYER.
